UNITED STATES PATENT OFFICE

HERBERT G. M. FISCHER, OF WESTFIELD, NEW JERSEY, ASSIGNOR TO STANDARD OIL DEVELOPMENT COMPANY, A CORPORATION OF DELAWARE

PROCESS FOR PURIFICATION OF HYDROCARBON OILS

No Drawing. Application filed August 19, 1927. Serial No. 214,215.

The present invention relates to the art of purifying and refining hydrocarbon oil and more specifically comprises an improved process for sweetening hydrocarbon oil such as heavy naphtha, kerosene, and the like. My invention will be fully understood from the following description.

Hydrocarbon oils such as heavy naphtha, kerosene and the like often contain sulphur bearing impurities, the presence of which is detected by the "doctor" test. This test is well known in the petroleum industry and has been fully described in Technical Paper 323 of the United States Bureau of Mines, page 83. Oils which do not pass this test are termed "sour" oils and it is customary to treat such oils with "doctor" solution, which is a solution of litharge in aqueous caustic soda and which is also called sodium plumbite. Treatment with "doctor" comprises agitation of the oil with the required quantity of "doctor" solution for a short time, followed by the addition of sulfur. If sufficient "doctor" is used, the oil will be sweet and the quantity of "doctor" required as well as sulfur is determined empirically on a small sample of the oil to be treated.

In sweetening very sour oils, a large quantity of "doctor" is required, but if the mixture of oil and "doctor" is blown with a strong current of air or other oxygen-containing gas, the oil may be sweetened with a relatively small quantity of "doctor". I have found that if sulfur is added during the blowing treatment in other than small quantities, the oil is contaminated by the formation of sulfur compounds, as indicated by discoloring on shaking with a small quantity of metallic mercury, and by the fact that the sulfur content of the oil is increased, both of which are undesirable. My improved process reduces the quantities of both "doctor" and sulfur used in treating, does not appreciably increase the sulfur content of the oil, and the oil does not sensibly darken on shaking with mercury and is much improved in respect to color holding properties and burning quality.

In my process less than that quantity of "doctor" solution required to sweeten a sam-

ple of oil to be treated is added to the oil but I preferably use not more than 50% and generally between 10 and 50% of that required. By that required, I mean the quantity of "doctor" necessary to sweeten the oil in the absence of a current of air or other oxygen containing gas. The mixture is agitated by any suitable means and in most cases the current of air is sufficient for agitation. Agitation is continued from 4 to 10 hours, depending on the nature of the oil.

The mixture of oil and "doctor" is preferably blown with air for about one hour before addition of sulfur and sulfur is then added in a plurality of batches with a blowing period after each addition. I prefer to add the major quantity of sulfur in the first two batches which are preferably equal to one half that required to react with the lead oxide in the "doctor". Subsequent batches of sulfur are relatively small preferably not exceeding 2½ pounds of sulfur per 1000 barrels of oil being treated. The small subsequent batches of sulfur are added until the oil is sweet and blowing with air is continued for about one hour after each addition.

As an example of my process the following is illustrative. A sour rerun kerosene from Regan crude has the following characteristics:

Gravity	42.5° A. P. I.
Sulfur content	100%
Color	19 Saybolt
Color after 16 hours at 212° F.	14 Saybolt

In treating a small sample it was found that 6500 barrels of oil require 8050 pounds of PbO in 2500 gallons of aqueous caustic soda for sweetening and 1155 pounds of sulfur should be added, sweetening being carried on in the absence of air or at least, with only sufficient air for agitation. To 6500 barrels of the oil, above mentioned, 4000 pounds of PbO is added, a part being dissolved in 2500 gallons of 18° Bé. caustic soda and this mixture is blown with a strong current of air for about one hour. The major quantity of sulfur is then added in two batches of 288 pounds each, followed by blowing for about one hour. The oil is

found to be sour and requires two further batches each of 16 pounds of sulfur to effect sweetening, and air blowing is continued for about one hour after each addition as will be understood. The blowing time is in all five hours. The mixture is allowed to settle, the aqueous layer drawn off and the oil is washed thoroughly with water. The oil then has the following characteristics:

- 10 Gravity ----- 42.5° A. P. I
- “Doctor” ----- Passes
- Sulfur content ----- 103%
- Color ----- 21 Saybolt
- Color after 16 hrs. at 15 212° F ----- 19 Saybolt
- Corrosion copper strip ----- O. K.
- Mercury test ----- Very slight, passable

My invention is applicable primarily to 20 very sour oils but maybe used in sweetening only slightly sour oils. It may be used to sweeten kerosene and various heavy naphthas. My invention is not to be limited by a theory of the mechanism of the various chemical reactions, nor by any example given merely by way of illustration, but only by the following claims, in which I wish to claim all novelty inherent in my invention.

I claim:

- 30 1. An improved process for treating hydrocarbon oil, comprising agitating with litharge and aqueous caustic soda, blowing a strong current of an oxygen containing gas through the mixture and successively adding 35 small quantities of sulphur during the blowing, whereby the formation of undesirable sulphur compounds is substantially prevented.
- 2. An improved process for sweetening 40 hydrocarbon oil, comprising agitating with “doctor,” simultaneously blowing a strong current of air through the mixture for a prolonged period and successively adding small quantities of sulphur during blowing whereby the formation of undesirable sulphur compounds is substantially prevented.
- 3. An improved process for refining sour 45 hydrocarbon oil, comprising agitating with “doctor,” in quantity less than sufficient to sweeten the oil in the absence of oxygen, blowing a strong current of air through the mixture for a prolonged period and adding sulphur in successive small quantities during the blowing whereby the formation of undesirable sulphur compounds is substantially prevented.
- 4. An improved process for refining sour 50 hydrocarbon oil comprising adding “doctor” solution not in excess of 50% of that required in the absence of air blowing, blowing with a strong current of air, adding sulphur in small regulated amounts and continuing the blowing whereby formation of undesirable sulphur compounds is substantially prevented.

5. A process according to claim 4 in which the mixture of oil and “doctor” is blown with air for a prolonged period after each addition of sulphur.

6. A process according to claim 4 in which the mixture of oil and “doctor” is blown about one hour before addition of sulphur and about one hour after each addition of sulphur.

7. An improved process for sweetening 75 hydrocarbon oil comprising agitating the oil with “doctor” in an amount equal to 10 to 50% of that required in the absence of air blowing, blowing a strong current of air through the mixture, adding sulphur to the mixture in two major batches each, followed by about one hour air blowing, said batches not exceeding .072 pounds per pound of litharge, and thereafter adding sulphur in relatively small hourly batches each followed by air blowing for about one hour until the oil is sweet.

8. A process according to claim 7 in which the relatively small subsequent batches of sulphur are not in excess of 2.5 pounds per 80 1000 barrels of oil treated.

HERBERT G. M. FISCHER.
